STOVE HANDLE

Donald E. Stewart, Grandville, Mich., assignor to
Winters & Crampton Corporation, Grandville,
Mich., a corporation of Michigan

Application November 28, 1949, Serial No. 6,298

Term of patent 7 years

(Cl. D81—25)

To all whom it may concern:

Be it known that I, Donald E. Stewart, a citizen of the United States, residing at Grandville, in the county of Kent and State of Michigan, have invented a new, original, and ornamental Design for a Stove Handle, of which the following is a specification, reference being had to the accompanying drawing, forming part thereof.

Fig. 1 is a plan view of a stove handle embodying my new design.

Fig. 2 is a front elevation of the same.

Fig. 3 is a right hand end view of the same, and
Fig. 4 is a section on line 4—4 of Fig. 1.

I claim:

The ornamental design for a stove handle, substantially as shown.

DONALD E. STEWART
